UNITED STATES PATENT OFFICE.

FRANCIS MAXWELL HENRY AND JOHN GUNN MADDEN, OF MINNEAPOLIS,
MINNESOTA.

CONCRETE CONSTRUCTION.

No. 825,052.

Specification of Letters Patent.

Patented July 3, 1906.

Application filed October 4, 1904. Serial No. 227,159.

To all whom it may concern:

Be it known that we, FRANCIS MAXWELL HENRY and JOHN GUNN MADDEN, of Minneapolis, Hennepin county, Minnesota, have invented certain new and useful Improvements in Concrete Construction, of which the following is a specification.

The object of our invention is to provide means for holding concrete-cement or other self-setting substance in position while under construction until it partially or entirely sets, said means being removable without in any way disturbing the structure built around it.

The invention consists generally in various constructions and combinations, all as hereinafter described, and particularly pointed out in the claims.

In the accompanying drawings, forming part of this specification, Figure 1 is a top view of a collapsible core or mold used in the formation of pipes. Fig. 2 is a vertical sectional view on the line 1 2 of Fig. 1. Fig. 3 is a vertical sectional view on the line 3 4 of Fig. 1 substantially at right angles to the section-line of Fig. 2. Fig. 4 is a detail sectional view on the line 5 6 of Fig. 1. Fig. 5 is a similar view on the line 7 8 of Fig. 1. Fig. 6 is a detail view illustrating the joint between the sections of the shell of the mold. Fig. 7 is a detail view showing a portion of the shell in its collapsed position. Fig. 8 is a detail view showing the means for attaching the operating-arms to the mold-shell. Fig. 9 is a top view of a modified construction. Fig. 10 is a vertical sectional view of the same. Fig. 11 is a detail view showing the position of one of the wedges between the sections of the mold-shell. Fig. 12 is a top view similar to Fig. 9, showing the device collapsed. Fig. 13 is a vertical sectional view of Fig. 12. Fig. 14 is a detail view showing the collapsed position of one of the wedges. Fig. 15 is a detail view showing the manner of attaching the operating-arms to the sections of the mold-shell.

In the drawings we have shown the mold-shell divided into four vertical sections, which we will designate by reference-letter A. There may be a greater or less number of these sections used, as preferred, and all of them forming when in use a substantially cylindrical mold-shell around which the concrete or other structure is formed.

B is a rod centrally arranged with respect to the shell, to which at intervals arms C and D are hinged at their inner ends, as at D', the outer ends of said arms being hinged to the sections A, as at E and F. These arms have the functions of toggle links or levers, being adapted when standing obliquely with respect to the rod B to draw in the sections of the shell toward the center and collapse the mold and to force the said sections outwardly to expand the mold when swung to a position at right angles to the rod B, as shown in Fig. 2. By means of the slots E' in the connections E between the arms C and the sections of the mold the said arms will have a limited initial movement without affecting the shell-sections with which they are connected. The arms D, however, having an ordinary pivotal connection with their sections will immediately operate them as soon as the rod B is moved. Consequently the shell-sections connected with the arms D will move ahead of the others both when the shell is extended and collapsed, and in the operation of the mold the shell-sections, connected, respectively, to the arms C and D, will not interfere with one another. We prefer to provide slotted lugs J secured at intervals to the sections of the shell and a ring or hoop I passing through the slots in said lugs for the purpose of holding the sections of the shell in their proper relative position, but allowing them to be moved in and out to contract or expand the mold. A cover G may be provided for the mold.

The use of the slots E' is not absolutely essential. In some instances the difference in the travel of the arms D and C will be sufficient to produce the desired movement of the sections—i. e., the arms C, as indicated in Fig. 2, are substantially at right angles to the rod B, and the arms D are obliquely arranged with respect to said rod when in their locked position. When, therefore, the rod B is moved lengthwise, the arms D will have a greater initial movement than the arms C, and consequently the sections connected with the arms D will move before those connected with the arms C, and practically the same result is therefore obtained without the employment of the slots E'.

In Fig. 9 we have shown a modified construction which consists in providing a shell composed, preferably, of three vertical sections L, between the joints of which a corre-

22

sponding number of vertical bars M, wedge-shaped in cross-section, are arranged for the purpose of separating or spreading the contiguous edges of the sections. A rod O is concentrically arranged with respect to the shell and is pivotally connected by arms P and R, respectively, with the shell-sections and with the bars M. These arms P and R have the same functions heretofore described with reference to Figs. 1, 2, and 3, and the arms P have the same sliding connections with their shell-sections as the arms C, heretofore described, and consequently the wedge bars will move both ways in advance of the shell-sections. The wedge bars may be of any suitable size, and there may be any suitable number of them, according to the character of the structure that is being built.

An apparatus of this kind can be used in the manufacture of hollow building-blocks, posts, &c., and in the construction of tanks, conduits, sewers, or any hollow structure of plastic material which sets or hardens after being formed around a mold.

25 In the operation of the modified construction the wedge bars engaging the beveled contiguous edges of the shell-sections will force them apart and expand the mold to its normal working position. When the mold is collapsed, the wedge bars will be withdrawn and allow the contraction of the shell-sections and their separation from the inner surface of the structure formed around them.

We claim as our invention—

35 1. A cylindrical mold comprising a shell divided vertically into a series of sections, a rod longitudinally movable in said mold, arms pivotally connecting said rod at intervals with the respective shell-sections, and means whereby some of said sections will move before the other sections in expanding and collapsing the mold, substantially as described.

45 2. A collapsible mold comprising a shell divided vertically into a series of sections, a series of arms pivotally connected to said sections, an operating-rod connected with said arms and some of said arms having a sliding attachment with their sections, for the purpose specified.

50 3. A collapsible cylindrical mold divided vertically into a series of sections, bars wedge-shaped in cross-section provided between the contiguous edges of the shell-sections, arms pivotally connected to said shell-sections and to said bars respectively, an operating-rod pivotally attached to the inner ends of said bars, and means whereby said mold-sections will remain stationary during a predetermined initial movement of said wedge bars in both directions, substantially as described.

4. A collapsible mold comprising a shell divided vertically into independent sections, vertical bars wedge-shaped in cross-section provided between the contiguous edges of said sections, an operating-rod, arms pivotally connecting said rod with said shell-sections and with said bars, the arms connecting said rod and said sections having a sliding attachment with the latter whereby said sections will remain stationary during the initial movement of said wedge bars in both directions, substantially as described.

5. A mold comprising a cylindrical shell divided vertically into a series of sections, an operating-rod, a series of arms pivotally connected to said rod and to said sections, said sections having a series of inwardly-projecting slotted lugs, and a hoop passing through said lugs and whereon said sections are slideable in and out to contract or expand the mold, substantially as described.

6. A mold comprising a shell divided longitudinally into a series of sections, a rod longitudinally movable in said mold, arms pivotally connecting said rod at intervals with the respective shell-sections and some of said arms forming greater angles with said rod than the angles formed by other arms and said rod, for the purpose specified.

7. A cylindrical mold divided into a series of sections, bars wedge-shaped in cross-section, provided between contiguous edges of the shell-sections, arms pivotally connected to said shell-sections and to said bars respectively, an operating-rod pivotally attached to the inner ends of said bars the arms connecting said rod with said shell-sections being substantially at right angles to said rod, and the arms connecting said rod and said bars being obliquely arranged with respect to said rod when the mold is in its expanded position, substantially as described.

8. A mold divided longitudinally into a series of sections, bars wedge-shaped in cross-section provided between the contiguous edges of the shell-sections, arms pivotally connected to said shell-sections and to said bars respectively, an operating-rod pivotally attached to the inner ends of said bars, and means whereby said mold-sections will remain stationary during a predetermined initial movement of said wedge bars in both directions, substantially as described.

In testimony whereof we have signed our names to this specification, in the presence of two subscribing witnesses, October 1, 1904.
